UNITED STATES PATENT OFFICE

2,368,410

CURRENT-LIMITING CONTROL FOR ELECTRIC DISCHARGE DEVICES

John H. Campbell and John O. Aicher, Cleveland Heights, Ohio, assignors to General Electric Company, a corporation of New York

Application January 16, 1942, Serial No. 427,034

9 Claims. (Cl. 176—122)

This invention relates to electric discharge devices, and especially to current-limiting control for such devices. The invention is very useful for fluorescent tubes or lamps of the usual positive column discharge type, and is hereinafter explained with particular reference to lamps of this character.

As a general rule, discharge devices or lamps require special provisions for limiting the discharge current as against its natural tendency to increase automatically without any corresponding increase in the supply voltage, as a result of which the lamp would "run away" and destroy itself. Such current-limiting means may assume various forms, such as ballast resistors or inductances, for example. Inductances or chokes are widely used, since they also serve to provide a temporary high voltage for starting in cases where the normal supply voltage is insufficient for that purpose. However, there are other ways of doing this; and in cases where the electrode gap of the discharge device is not too long and the other conditions in the device at starting are favorable, starting may be effected on the normal operating voltage. This is true, for example, as regards standard fluorescent lamps of 18 inch tube length, 1½ inch diameter, 14 or 15 watt rating, intended for operation on supply circuits of 110-125 volts. Two such lamps can readily start and operate in series on a supply circuit of this voltage, as shown, for example, in United States Patent 2,266,619, December 16, 1941, John H. Campbell.

The necessity for special current-limiting equipment such as chokes or resistors complicates fluorescent lamp installations and increases their cost. It also introduces a factor of uncertainty into their operation, owing to the possibility that (through ignorance or carelessness) lamps may be used with unsuitable accessories. The resulting failure or unsatisfactory performance of the lamps tends to reflect unjustly on the lamp manufacturer.

The present invention aims at overcoming these drawbacks by including all necessary current-limiting provisions in the lamp itself. From the following description of species and forms of embodiment of the invention, and from the drawing, various other features and advantages will become apparent.

In the drawing, Fig. 1 is a general view of a fluorescent tube or lamp embodying the invention, including suitable operating and starting circuits diagrammatically represented; Fig. 2 is a fragmentary tilted or perspective view of an

electrode mount such as shown in Fig. 1, on a larger scale; and Figs. 3 and 4 are similar views of modified forms of electrode mount.

Fig. 1 shows a fluorescent tube lamp L of the positive column electric discharge type with a tubular envelope 10 having spaced-apart thermionic cathodes 11, 11 in its ends, which may be specially preheated for starting, and are shown connected across a power supply circuit P including the manual make-and-break switch 13, but without any current-limiting means therein. The envelope 10 may contain a low-pressure atmosphere of starting gas, such as argon at a pressure of 2 to 5 mm. of mercury, and also a vaporizable and ionizable working substance such as mercury. A supply of mercury, which may exceed the amount that will vaporize during operation of the lamp L, is indicated by a drop 14 inside the envelope 10, and an internal coating 15 of fluorescent material or phosphor on the envelope walls is also indicated. A starting and electrode-heating circuit H is shown connected across the circuit P through the filamentary cathodes, 11, 11, with a starting switch S included therein, which may be of thermal type or of any other suitable type. The lamp L is equipped with ordinary bipost bases 18 whence current leads 19, 19 extend into the interior of the envelope 10, which is shown with separate glass end portions of stem and flare type.

As shown in Figs. 1 and 2, the cathodes 11, 11 are just alike, and are of coiled or "coiled-coil" filamentary type. Each cathode 11 comprises an emissive coil of refractory metal wire (preferably tungsten), which is coiled into a larger coil 20, and is connected between support and connector wires 22, 22, as by having each end clamped into a sharp reverse bend 23 of the corresponding wire 22. One end of each wire 22 extends laterally and at right angles to the coil 20, and has its lower extremity fused into the upper end of the glass lamp mount stem 25. The other end portion 26 of each wire 22 is bent to extend parallel with the coil 20 to serve as an auxiliary anode 45 during the positive half-cycles of operation.

The current lead-wires 19, 19 of each lamp mount extend inward through the hollow stem 25 into the interior of the discharge envelope 10, being sealed through the closed inner end of the stem as usual. The inner ends of these leads 19, 19 are preferably bent outward from one another and then upward again, as shown at 29, 29. Between each lead end 29 and the corresponding outer end of the cathode coil 20 a balance resistance 30 is interposed and connected.

as by welded joints 31, 31, being here shown as a coil or coiled coil more or less similar to the coil 20, and preferably of tungsten, but unemissive or substantially so. In effect, therefore, the current leads 29, 29 are interconnected by three resistance members comprising an emissive thermionic coil 20 with unemissive ballasting end coils 30, 30. The coil 20 may be activated with a coating of refractory oxides, as of barium and strontium, as indicated by strippling, while the flanking ballast coils 30, 30 are unactivated and are preferably made of larger gauge wire than the coil 20, so as to insure that they shall be substantially unemissive under all conditions of operation.

The construction shown in Fig. 3 differs from that in Fig. 2 in having the lower ends of the cathode-coil support and connector wires 22, 22 insulatively connected to the upper ends of the lead wires 19a, 19a (instead of to the upper end of the stem 25), as by means of glass beads 35, 35 into which the wire ends are fused. Each ballast coil 30a extends up and down parallel with adjacent wires 22, 19a and has its ends bent at right angles to the coil and connected to said wires by welded joints 31a, 31a.

The construction shown in Fig. 4 differs from that in Fig. 3 in having an externally activated unipotential metal cathode tube 40 mounted around the tungsten wire coil 20b, which latter merely serves as a separate cathode resistance heater, without being itself effectively emissive. As shown, the ends of the tube 40 are closed by apertured end walls 41, 41 whose openings have insulative bushings 42, 42 through which extend the coil connectors 22b, 22b. The cathode tube 40 is electrically connected to the mid-point of the coil 20b, as diagrammatically indicated at 44, so that its possible circuit connections through the current leads 19b, 19b are of equal resistance. To avoid difficulties in lamp exhaust or in cathode activation, the connection 44 may in practice be made as shown in United States Patent 1,903,496, April 11, 1933, Beck, Fig. 2.

In Figs. 3 and 4, various parts and features are marked with the same reference numerals as their homologues in Fig. 2, in order to dispense with repetitive description, distinctive letters being added where such distinction appears needful.

The discharge device L being connected in the circuits P and H as shown in Fig. 1, a cold start of the lamp L may be initiated by closing the switch 13, which causes current to flow through both circuits—the starting switch S being initially closed or quickly closing in response to energization of the circuit H, if it is of glow-switch type. Current then flows through the circuits P, H and through each of the cathodes 11, 11 and both its associated ballast resistances 30, 30, preheating the cathode coils to proper emissive temperature. During this preheating and starting period, therefore, all four of the ballast resistances 30 are in circuit and are effective to limit the current flow. When the switch S opens, substantially or nearly the full voltage of the supply line P is felt between the cathodes 11, 11, and suffices to initiate a discharge between them. Thereafter the discharge current flows through the circuit P, the cathodes 11, 11, the two ballast resistances 30, 30 through which the cathodes are connected to the circuit P, and through the lamp tube L. The other two ballast resistances 30, 30 are now out of circuit and ineffective; but the resistance to the

discharge between the cathodes 11, 11 replaces them, and the two resistances 30, 30 that remain in circuit suffice to limit the discharge current and prevent the lamp L from running away. In practice, moreover, two of the lamps L may be run in series after starting has been accomplished in both.

By making the ballast resistances 30, 30 in the connections of the cathodes 11, 11 to the supply line P (Fig. 1) of suitable values, it is possible to omit the other two resistances 30, 30. This advantage, however, must be offset against the limitation of having either to "polarize" the device L mechanically so as to positively prevent improper connection into the circuits P, H, or else to accept the destruction of lamps due to unintelligent disregard of markings placed on them to indicate the proper mode of connection. Moreover, the two resistances 30, 30 must be of adequate values to take the place of the four shown in Fig. 1 during starting, while not of excessive values for subsequent normal operation of the device L.

The cathode and ballast arrangements shown in Figs. 2, 3, and 4 all function substantially alike in the lamp L. But the type of cathode shown in Fig. 4 affords the advantage of obviating radio interference due to proximity of the lamps to a receiving set, owing to the fact that the arc does not concentrate at one point on such a cathode as it does on the filamentary cathode now commonly used in fluorescent lamps, and hence does not produce the usual cathode sputtering which gives rise to interfering radio frequencies emanating from ordinary fluorescent lamps. In other words, lamps with the unipotential cathode give substantial freedom from both bulb radiation noise and line noise due to line feedback and line radiation.

For the convenience of those desiring to practice the invention, essential illustrative particulars of cathode mounts such as shown in Figs. 2 and 3 are here given:

The cathode 20 in Figs. 2 and 3 may consist of a coiled coil of tungsten wire of 2.5 mil diameter, first wound 215 turns per inch on a 6 mil molybdenum mandrel to a coil length of 44.9 mm., and then wound 50 turns per inch on a 22.6 mil molybdenum mandrel to a coil length of 7.6 mm. The total exposed length of actual wire in the cathode coil 20 between the clamps 23, 23 may amount to 252 mm., having a cold resistance of 4.4 ohms. The cathode coil 20 may be activated with the usual oxide coating mixture of barium, strontium, and calcium oxides. Each of the ballasts 30 or 30a in Figs. 2 and 3 may consist of a coiled coil of tungsten wire of 2.75 mil diameter, first wound 180 turns per inch on a 7 mil molybdenum mandrel, and then wound 42 turns per inch on a 24 mil molybdenum mandrel. For each ballast coil 30, 30a may be used 18 turns of the larger coil, with an exposed wire length of 354 mm. between the end-welds 31, 31 or 31a, 31a, giving a cold resistance of 4.7 ohms for each ballast. Of course both molybdenum mandrels for each coil 20 and 30 or 30a are removed after winding, in the usual way.

What we claim as new and desire to secure by Letters Patent of the United States is:

1. A gaseous electric discharge device comprising a sealed envelope containing an ionizable medium and a pair of spaced mounts carrying electrodes and ballast resistances, each of said mounts comprising a pair of current conductors extending through a wall of said envelope and at

least two coiled filamentary resistance members in said envelope connected in series between said current conductors, one of said resistance members constituting a part of one of the electrodes of the device, the said electrode also comprising electron-emissive material, another of said resistance members being substantially unemissive and serving as a ballast member, the unemissive resistance members in said pair of mounts being designed to serve as substantially the entire ballast during operation of the device, and the electrodes in said pair of mounts being spaced for a discharge therebetween.

2. A gaseous electric discharge device comprising a sealed envelope containing an ionizable medium and spaced mounts carrying electrodes and ballast resistances, each of said mounts comprising a pair of current conductors extending through a wall of said envelope and three coiled filamentary resistance members in said envelope connected in series between said current conductors, the second resistance member constituting a part of one of the electrodes of the device, the said electrode also comprising electron-emissive material, the first and third resistance members being substantially unemissive and serving as ballast members, the electrodes in said mounts being spaced for a discharge therebetween.

3. The combination set forth in claim 2 wherein in the electrode in at least one of said mounts includes a metal shell surrounding said second resistance member and coated with electron-emissive material and electrically connected to the midpoint of said second resistance member.

4. The combination set forth in claim 2 wherein in the first and third ballast resistance members are made of heavier gauge wire than the second resistance member.

5. In a gaseous electric discharge device comprising a sealed envelope containing a pair of spaced electrodes between which the discharge occurs; one of said electrodes being incorporated in an electrode mount comprising a support member, a pair of lead-in conductors extending through said support member, and three coiled filamentary resistance members supported from said support member and connected in series between said lead-in conductors the second resistance member constituting a part of an activated electron-emitting electrode, the first and third resistance members being substantially unemissive and serving as ballast members and being located between the said support member and the said second resistance member.

6. In a gaseous electric discharge device comprising a sealed envelope containing a pair of spaced electrodes between which the discharge occurs; one of said electrodes being incorporated in an electrode mount comprising a support member, a pair of lead-in conductors extending through said support member, a support conductor attached to but insulated from the end of each of said lead-in conductors to form a mechanical continuation thereof, a coiled filamentary resistance member bridging and supported by said support conductors and constituting a part of an activated electron-emitting electrode, and a pair of substantially unemissive coiled filamentary resistance members each mounted on and having one end electrically connected to one of said lead-in conductors and the other end electrically connected to the adjacent support conductor so that the said resistance members are all electrically connected in series between said

lead-in conductors and said pair of unemissive resistance members serve as ballast members.

7. In a gaseous electric discharge device comprising a sealed envelope containing a pair of spaced electrodes between which the discharge occurs; one of said electrodes being incorporated in an electrode mount comprising a support member, a pair of lead-in conductors extending through said support member, a support conductor attached to but insulated from the end of each of said lead-in conductors to form a mechanical continuation thereof, a coiled filamentary resistance member bridging and supported by said support conductors and being surrounded by a metallic electrode shell electrically connected to the midpoint of said resistance member, and a pair of substantially unemissive coiled filamentary resistance members each mounted on and having one end electrically connected to one of said lead-in conductors and the other end electrically connected to the adjacent support conductor so that the said resistance members are all electrically connected in series between said lead-in conductors and said pair of unemissive resistance members serve as ballast members.

8. In a gaseous electric discharge device comprising a sealed envelope containing a pair of spaced electrodes between which the discharge occurs; one of said electrodes being incorporated in an electrode mount comprising a glass stem, a pair of support conductors extending from said stem and each having one end secured to said stem, a resistance member bridging said support conductors and supported thereby, said resistance member constituting a part of an activated electron-emitting electrode, a pair of lead-in conductors extending through said stem, and a pair of substantially unemissive resistance members each mounted on and having one end electrically connected to one of said lead-in conductors and the other end electrically connected to one of said support conductors so that the said resistance members are all electrically connected in series between said lead-in conductors and said pair of unemissive resistance members serve as ballast members.

9. In a gaseous electric discharge device comprising a sealed envelope containing a pair of spaced electrodes between which the discharge occurs; one of said electrodes being incorporated in an electrode mount comprising an insulative support member, a pair of spaced lead-in wires extending inwardly through said support member, a pair of conductors extending inwardly from the inner ends of said lead-in wires and secured thereto but insulated therefrom by glass beads fused to the adjacent ends of said wires and conductors, an activated electron-emitting electrode comprising a coiled filamentary resistance member extending laterally between and connected to the inner ends of said conductors, and a pair of unemissive coiled filamentary resistance members located one on each side of the mount and between the first-mentioned resistance member and the support member, each of said pair of resistance members being mounted on and having its ends connected to the adjacent lead-in wire and conductor to complete a circuit around the associated glass bead thereby connecting all three resistance members in series, the said pair of resistance members serving as ballast members.

JOHN H. CAMPBELL.
JOHN O. AICHER.
